[57] CLAIM

The ornamental design for a door stopper, as shown and described.

DESCRIPTION

FIG. 1 is a front elevational view of the door stopper showing my new design, the broken line showing of a portion of a door and floor being for illustrative purposes only;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

*FIG. 1**FIG. 2**FIG. 3**FIG. 4**FIG. 5**FIG. 6*
